UNITED STATES PATENT OFFICE.

EDWARD SLOSSON, OF RIVERSIDE, CONNECTICUT, ASSIGNOR TO W. G. CORNELL COMPANY, A CORPORATION OF NEW YORK.

DESIGN FOR A DRAFTING INSTRUMENT.

54,137.

Specification for Design.

Patented Nov. 4, 1919.

Application filed May 24, 1919. Serial No. 299,675. Term of patent 14 years.

To all whom it may concern:

Be it known that I, EDWARD SLOSSON, a citizen of the United States, residing at Riverside, in the State of Connecticut, have invented a new, original, and ornamental Design for a Drafting Instrument, of which the following is a specification, reference being had to the accompanying drawing, forming part thereof.

Figure 1 is a plan view of a drafting instrument illustrating my design; and

Fig. 2 is a section on the line 2—2 of Fig. 1.

I claim:

The ornamental design for a drafting instrument, as shown.

EDWARD SLOSSON.

Witnesses:

HENRY W. ARCHIBALD,
FREDERICK C. GRAESSLE.
